UNITED STATES PATENT OFFICE.

OTTO W. L. BUSS, OF MINNEAPOLIS, MINNESOTA.

WINDOW STRUCTURE.

Application filed October 27, 1924. Serial No. 746,226.

This invention relates to new and useful improvements in window structures such as are commonly employed in the construction of buildings, etc., and more particularly relates to such structures of the fire-proof type which are preferably constructed of metal and are provided with means for anchoring or securing them to the masonry of the wall in which they are installed. The form of structure here shown is of the type commonly known as basement windows comprising a frame and sash, and wherein the sash is usually pivotally mounted or hinged to the upper horizontal portion of the frame, although it is to be understood that the structure may be used for other purposes than basement windows and also that the sash may be vertically hinged to the frame or be rigidly secured thereto. The hinges for mounting the sash in the frame are preferably integrally formed from a portion of the metal from which the frame and sash are constructed thus obviating the necessity for the present common use of screws or rivets for securing the hinges thereto. The hinges are also so designed that the sash may readily be detached from the frame for washing or replacement of glazings, without the use of tools. Means are provided on the frame whereby the usual screens and storm sash may readily be secured thereto. The sash is also provided with a novel locking means which is preferably mounted in one or more of the muntin bars thereof and is adapted to cooperate with means in the frame to securely lock the sash thereto. The construction of this novel frame and sash is very simple and inexpensive, and is such that it may readily be manufactured on a production basis, thereby greatly reducing the manufacturing costs of the structure. The structure herein shown is an improvement over the form of window structures shown in my prior pending application filed November 21, 1923, Serial No. 677,040.

The object of this invention therefore is to provide an improved window structure.

Other objects of the invention will more fully appear from the following description and the accompanying drawings and will be pointed out in the annexed claims.

In the accompanying drawings there has been disclosed a structure designed to carry out the objects of the invention, but it is to be understood that the invention is not confined to the exact features shown, as various

changes may be made within the scope of the claims which follow.

In the drawings:

Figure 1 is a front view of the structure 60 showing the sash in closed locked position;

Figure 2 is a rear view of Figure 1 showing the means provided thereon for securing thereto the screen or storm sash;

Figure 3 is an enlarged detail sectional 65 view on the line 3—3 of Figure 1, partially broken away, and additionally showing how the frame of the structure is preferably secured to the opening in the basement wall;

Figure 4 is a partial sectional view of the 70 structure showing the means provided for retaining the sash in open position;

Figure 5 is a detail sectional view on the line 5—5 of Figure 3;

Figure 6 is a detail plan view of the lower 75 horizontal member of the frame showing the means provided therein for retaining the sash in open position as shown in Figure 4;

Figure 7 is a detail view of a lower portion of the sash showing one of the muntin 80 bars secured thereto and also showing how the locking bolts for locking the sash to the frame are preferably mounted in the muntin bars;

Figure 8 is a horizontal sectional view 85 on the line 8—8 of Figure 7;

Figure 9 is a vertical sectional view on the line 9—9 of Figure 7; and

Figure 10 is an enlarged detail view showing the socket provided on the lower frame 90 member to receive the end of the locking bolt to lock the sash to the frame.

The frame of the novel window structure featured in this invention preferably comprises upper and lower members and end 95 or side members. These frame members are preferably substantially Z-shaped in cross-section as particularly shown in Figures 3 and 5 and are suitably secured together at the corners of the frame by such means as 100 welding, thereby providing a very rugged and substantial frame. The Z-shaped frame members comprise a pair of spaced walls 14 and 15 and an intermediate inclined wall 16 interposed therebetween and connecting 105 together the walls 14 and 15. In mounting the frame in the opening provided in the foundation or building, the relatively wider wall 14 will be outwardly presented while the inner wall 15 will be inwardly presented. 110 Referring to Figures 3 and 5, it will be seen that the inner wall 15 of the frame is

preferably narrower than the outer wall 14 so that the inwardly projecting edge 17 of the outer wall will overhang the inner rounded edge 18 of the inner wall 15, thereby providing a dual seat against which the sash is adapted to be seated as shown in the drawings. It will be seen that the area defined by the outwardly projecting edge 19 of the outer wall is relatively greater than the area defined by the outer edge 21 of the wall 15, so that the outer edge 19 will thereby overhang the outer edge of the inner wall 15. Thus, when the frame is positioned within the opening provided in the wall of the foundation or building as shown in Figures 3 and 4 and 5, the frame will be supported by the outwardly projecting corner or edge 19 of the outer wall 14, and the triangular space between the inner wall 15 and the inclined wall 16 may then be filled in with mortar or masonry to securely anchor the frame to the foundation. Integral loops 22 are preferably pressed out of the metal of the outer wall 14 of the upper frame member to provide additional means whereby the frame may be secured to the wall of the foundation or structure. Nails may be inserted into these loops and driven into the wall or joists, as indicated by the dotted lines in Figure 3 thereby holding the frame permanently in place.

Means are also provided on the outer walls 14 of the end frame members for securing the usual storm sash or screen to the frame, such means preferably consists in outwardly bending or forming a portion of metal, as particularly shown in Figure 5, to form loops 23 adapted to receive a suitable fastening means provided for securing the storm sash or screens to the frame. I have here shown two such loops on each side frame member. Similar loops 24 are provided in the outer wall of the lower frame member. These loops are preferably arranged relatively close to the lower edge 19 of the frame and function to provide a drain for water which might get into the triangular space 25 provided between the outer wall 14 and the inclined wall 16 of the lower frame member.

The novel sash featured in this invention is preferably constructed of metal and so formed as to have a cross-section of irregular shape. An outwardly projecting marginal flange 26 is provided on the sash adapted to overlap the inwardly projecting edge 18 of the inner wall 15. This flange is adapted to be seated against the inner face of the wall 15 as shown in Figures 3 and 5. A seat 27 is provided on the outer portion of the sash and is adapted to be seated against the inner face of the outer wall 14. As here shown the wall of the sash is also formed to provide an outwardly projecting flange 28 adapted to be fitted within

the relatively smaller opening of the frame defined by the inner edge 17 of the outer wall 14. This flange functions to reinforce the outer portion of the sash and also to provide a drip to prevent water flowing over the surface of the glazings from entering the triangular space 25 of the frame. A seat 29 is provided in the sash frame adapted to receive a pane of glass 31 which may be secured thereto by such means as the usual putty 32. The pane of glass is preferably mounted in an intermediate position in the sash as shown, and the metal from which the sash is constructed is so formed as to present an inclined face 33 adapted to encircle the pane, thereby providing a sash of very neat appearance and also of very rugged construction.

The novel means provided for pivotally connecting the sash to the frame preferably consists in upwardly bending a portion of the inner wall 15 of the upper frame member to form a pair of hooks 34 shown in Figures 3 and 4. The upper portion of the sash is preferably provided with a projecting inclined flange 35 which functions to reinforce and strengthen the upper portion of the sash when connected to the frame. Apertures 36 are provided in the upper flange 26 of the sash adapted to receive the upturned hooks 34 of the frame whereby to provide a supporting means for the sash when mounted in the frame. Thus it will be seen that by means of the hooks 34 and apertures 36 a hinged connection will be provided for the sash thereby allowing it to be swung to an open position as shown in Figure 4. The upper ends of the hooks 34 are preferably spaced a suitable distance from the walls 15 of the frame member 11 so that, when the sash is raised to a substantially horizontal position (shown in dotted lines in Figure 4), the sash may readily be detached from the frame without the use of tools. When the sash is mounted in the hooks 34, as shown in Figures 3 and 4, the marginal edge of the inclined flange 35 provided on the upper portion of the sash will engage the concave faces of the hooks and thereby tend to force the marginal flange 26 of the sash against the walls 15, thereby to provide a tight joint to prevent the entrance of air through the structures.

Means are also provided for holding the sash in open position as shown in Figure 4. Such means preferably consists in the provision of a bar 37, having a T-shaped head 39 on one end thereof, which is mounted in an aperture 40 provided in the inclined wall 16 of the lower frame member. (See Figures 4 and 6). A hook 38 is preferably formed at the other end of the bar 37 and is adapted to engage the projecting edge 28 of the sash, when in extended sash-opening position as shown in Figure 4. When the

sash is in closed position the bar 37 will be swung to the full line position in Figure 6, in which position it will be disposed within the triangular space 25 of the frame and will thus be concealed from view. When it is desired to open the sash the bar 37 may readily be grasped and swung to the position shown in Figure 4, in which position the hook 38 will be brought into engagement 5 with the projecting edge 28 and the bar will thus retain the sash in open position.

In Figures 1 and 2, there is shown a sash comprising three sections, such sections being provided by interposing the muntin bars 15 41 between the upper and lower members of the sash and suitably securing them thereto by such means as welding. Referring to Figure 8, it will be seen that the muntin bars 41 are preferably formed of metal and are 20 substantially triangular in cross-section. Each muntin bar is provided with an outwardly projecting flange 42 formed by folding the sheet metal from which the bar is made so that the opposed sides of the sheet 25 will be in abutting relation as shown. By thus forming the muntin bars, a seat 43 will be provided on each side thereof adapted to cooperate with the seat 29 in the sash frame to provide a continuous seat for the pane of 30 glass when seated therein. The flange 42 will also provide a division between the sash sections and will form a backing for the putty 32 when the pane of glass has been seated in the sash and secured thereto.

35 Another important feature of this invention resides in the novel means provided for securely locking the sash to the stationary frame of the structure. Such means preferably consists in the provision of suitable 40 locking bolts 45 which are slidably mounted in the muntin bars adjacent the lower portion of the sash. Each locking bar is provided with a finger grip 46 which outwardly projects therefrom through an elongated 45 opening 47 provided in the outer central portion of the muntin bar. This finger grip functions as a means whereby the locking bars may be slidably moved into and out of engagement with the lower member of the 50 stationary frame. An aperture or socket 48 is provided in the inclined wall 16 of the lower frame member and is adapted to receive the lower end of the locking bolt when the latter is moved into sash-locking position 55 as shown in full lines in Figure 3. Thus it will be seen that when the locking bolts are moved from the position shown in Figure 9 to that shown in full lines in Figure 3, the lower ends of the bolts will enter the socket 60 48 back of the inner wall 15 of the lower frame member thereby securely locking the sash to the frame. When the locking bolts are upwardly moved to the position shown in full lines Figure 9, the lower ends thereof will be moved out of engagement with the

sockets 48 and the sash may then be readily opened, as shown in Figure 4. Apertures 49 are preferably provided in the muntin bars adapted to receive a common form of padlock such as indicated by the dotted lines in 70 Figures 7 and 9 so that the locking bars may be locked in sash-locking position, thereby preventing the sash from being opened until the padlock has been removed from the apertures 49. 75

In the drawings, there is shown a window structure of the general shape and form commonly employed in the foundations of buildings but it is to be understood that the window structure may be made in various shapes 80 and forms and may employ one or more muntin bars; or, if desired, may be made without the use of any muntin bars. The sash may also be rigidly secured to the frame, thereby eliminating the use of the hinged 85 connection formed by the hooks 34 and apertures 36 and also eliminating the use of the sash locks provided by the locking bolts 45.

The frame and sash of this novel structure are also substantially of fireproof construction thereby providing such a structure which is well adapted for use in fireproof buildings. By the employment of the dual sash-receiving seat provided by the inwardly projecting edge portions of the spaced walls 90 14 and 15, and against which the sash is seated when in closed position, an air space will be provided around the sash which will prevent cold air from entering through the joint between the frame and sash. The 100 above construction will also prevent the surface of the inner frame wall 15 from becoming frosted in cold weather. It will also be seen that the frame and sash are constructed of metal thereby providing a very rugged 105 and substantial structure of comparatively light weight. Its construction is also very simple and inexpensive and it may therefore readily be manufactured on a production basis, thereby greatly decreasing the manufacturing cost. In the drawings, I have shown the use of putty for securing the 110 panes of glazings to the sash frame, but it is to be understood that other means may be employed for the above purpose without departing from the invention. 115

Having thus described my invention what I claim as new and desire to secure by Letters-Patent, is:

1. A window frame having an intermediate inclined portion terminated at opposite ends respectively by acute angularly related flanges inner and outer, the first extending downwardly and the other upwardly to form inner and outer frame faces, 120 the size of the opening defined by the inner flange being of greater area than that defined by the outer flange, and a sash pivoted to the inner flange and having portions sealingly engageable with the flanges, to 125 130

close both openings, all sides of the frame being cross-sectionally identical.

2. A window frame having an intermediate portion providing an inclined drain surface terminated at opposite ends respectively by acute angularly related flanges extending in opposite directions, the junction of the one flange with the inclined portion defining an opening of one size and 10 the free end of the other flange defining an opening of smaller size, the latter flange having drain openings.

3. A frame for the purpose described having continuous marginal flanges, inner and 15 outer, forming the corresponding faces of the frame, and connected by a section slanting from the inner periphery of the inner flange downwardly and outwardly to the outer periphery of the outer flange, the 20 inner opening defined by the inner flange being of greater area than that defined by the outer flange, and each flange being adapted to form a stop, and a sash having a body adapted to pass through the larger 25 inner opening and sealingly abut the larger flange at its inner side, and further having a flange to abut the outer side of the inner flange.

4. A window frame having all sides of 30 like cross-sectional configuration, each side having an intermediate portion terminated at opposite ends respectively by acute angularly related flanges extending in opposite directions, and forming the inner and outer 35 faces of the frame, the line of junction of one flange with the inclined portion defining an opening of one size, and the free end of the other flange defining an opening of smaller size.

40 5. In a window frame comprising upper, lower and side members having their ends secured together to form substantially a rectangular frame, each of said members being substantially Z-shaped in cross-section 45 and having the inwardly projecting edges of the spaced walls thereof arranged to form a seat to receive a sash, means on said members for securing the frame to the wall of a building, and integral means on said 50 members removably to secure a storm-sash or screen to the window frame.

6. In a window structure, comprising a metallic frame and sash therefor, the frame being substantially Z-shaped in cross-section, 55 a portion of the metal of said frame being upturned to form a supporting means for the sash, the sash having a projecting marginal flange adapted to be seated against one face of the frame, and said marginal 60 flange having apertures to receive the upturned portion of the frame thereby to pro-

vide a pivotal connection between said frame and said sash.

7. In a window structure, comprising a metallic frame and sash therefor, the frame being substantially Z-shaped in cross-section, 65 a portion of the metal of said frame being upturned to form a supporting means for the sash, the sash having a projecting marginal flange adapted to be seated against one face of the frame, and said marginal flange having apertures to receive the upturned portion of the frame thereby to provide a pivotal connection between said frame and said sash and means pivotally connected 70 to said frame adapted to engage said sash when opened, to retain it in such open position.

8. In a window structure, the combination of a frame and hinged sash therefor with a member having one end pivotally connected to the frame and having its other end adapted to contact with the sash to retain it in open position when said member is in working position, and the frame having a recessed portion adapted to receive said member when in its inoperative position.

9. In a window structure, the combination of a frame and sash therefor, means integrally formed on said frame adapted to cooperate with complementary means integrally formed on the sash to provide a hinged connection between said frame and sash, the sash having a cross member arranged therein to divide it into a plurality of sections each adapted to receive a pane of glass, and means operably mounted in said cross-member adapted to cooperate with means in said frame to provide a lock for the sash when in closed position.

10. In a window structure, the combination of a sash having a recessed muntin bar, a locking element movably mounted in the recess of the muntin bar and adapted to lock the sash to a frame, and means on the muntin bar to receive a supplemental locking means whereby said element may be held in sash-locking position.

11. In a window structure, the combination of a sash having a muntin bar, said bar having a hollow enclosed portion, a locking element operably borne within said hollow portion and adapted to be moved to lock the sash to a frame, said bar also having an elongated aperture adjacent said hollow portion, and a handle for the locking element extending through said aperture for operation of said element.

In witness whereof, I have hereunto set my hand this 24th day of October, 1924.

OTTO W. L. BUSS.
